UNITED STATES PATENT OFFICE.

JAMES POWERS, OF NEW YORK, N. Y.

TRANSFERRING MASTER-DRILL DEVICE.

1,310,034.

Specification of Letters Patent. Patented July 15, 1919.

Application filed June 6, 1917. Serial No. 173,093.

To all whom it may concern:

Be it known that I, JAMES POWERS, a citizen of the United States, residing in New York, in the county of New York and State 5 of New York, have invented certain new and useful Improvements in Transferring Master-Drill Devices, of which the following is a specification.

This invention relates to transferring or 10 profiling machines or devices and more particularly to master transferring devices for drills and other similar machine tools.

One object of this invention is to provide a machine of this kind which is simple and 15 economical in construction, efficient in operation and easy to manipulate.

Another object is to provide convenient 20 forms of tables for positioning guide plugs or pins for positioning the drill or similar tool.

Another object is to provide a convenient means for changing from one kind of drill or 25 tool to another without removing them from their chucks or holders.

These and other objects will appear as the 30 description proceeds; and it is understood that the invention is not limited to the particular constructions described since these may be greatly varied without departing from the scope of the appended claims.

In the accompanying drawings showing, 35 by way of example, several of many possible embodiments of the invention,

Figure 1 is a front elevation of the machine;

Fig. 2 is a side elevation, partly in section;

Fig. 3 is a plan;

Fig. 4 is a perspective view of one form of 40 positioning table;

Fig. 5 is a perspective view of a positioning plug adapted to be secured to the table of Fig. 4;

Fig. 6 is a perspective view of the adjustable support for the pilot spindle, the drill 45 or tool spindle and the driving means for the drill or other tool;

Fig. 7 is a perspective view of another form of positioning table;

Fig. 8 is a perspective view of a positioning pin adapted to be secured on the table of 50 Fig. 7.

The column 10 forming the frame of the machine is provided with a lateral bracket 11 on which is secured the positioning table 12.

On the front face of the column 10 is provided a vertically extending dovetailed guide 55 on which is adjustably received the grooved tool or work knee or table 14 held in adjusted position by means of the screw clamps 15.

The upper part of the column 10 is carried 60 upwardly and rearwardly to form an extension 16 (Fig. 2) in which is slidably carried the V-shaped supporting arm 18 adapted to be locked in place by the lock clamps 17 and to be slidably moved by the pinion 19 rotated by the handle 20 and engaging the rack 21 secured to the edge of the supporting arm 18.

The forward end of the supporting arm 18 carries transversely thereto the horizontal 70 support 22 on which are mounted gibs 23 forming a slideway in which is carried a slide 24 adapted to be locked therein by the screw lock 25 and to be horizontally moved 75 therein by means of the small pinion 26 engaging a rack 27 secured to the lower part of the slide.

On the front face of the end of the slide 24 over the tool knee 14, there is secured a bracket head 28 in which vertically slides 80 the spindle sleeve 29 provided at its rear part with a vertical rack 30 engaged by a suitable pinion (not shown) controlled by the handle 31, whereby the spindle sleeve is raised and lowered.

Rotatable within the sleeve 29 is a drill 85 chuck spindle 32 carrying at its lower end a chuck 34 for the drill 35 or other tool. The upper part of the spindle 32 is provided with the usual longitudinal key way in which 90 engages a key fixed in the bore of the helical gear 36 carried between the bearing arms 38 connected by the yoke 39 provided with a bearing base receiving the drive shaft 40 carried in the bracket-bearings 41 mounted 95 on the support 22.

The shaft 40 is provided with a key-way 42 adapted to receive the key 43 of a helical gear 44 engaging the worm gear 36 and 100 slidably on the drive shaft 40 and constrained by said key and key-way to rotate therewith.

On the inner end of the drive shaft 40 there is secured a bevel gear 45 engaged by the driving bevel gear 46 mounted on the end of the countershaft 48 carried by the bracket-bearings 49 and 50 mounted respectively on the horizontal support 22 and on a plate 51 secured on top of the extension 16.

10 A motor 52 mounted on a plate 54 secured to the top of arm 18 is provided with a motor shaft 55 carrying a pulley cone 56 from which power is transmitted by means of the belt 58 to the pulley cone 59 mounted on the countershaft 48.

15 On the end of the slide 24 over the positioning table 12 is disposed the supporting bracket 60 in which is vertically slidably mounted the pilot spindle 61 provided at its rear part with a rack 62 engaged by a pinion controlled by the handle 64, whereby the pilot spindle may be raised and lowered.

20 On the lower end of the pilot spindle is formed a chuck 65 adapted to receive the shank of a guide 66 held in place by a set screw 68 and provided with a guide base 69 in the lower end thereof.

25 The positioning table 12 is secured to the lateral bracket 11 by means of screws 70 and 71, the screws 71 serving also to secure on the table the locating scales 72 which serve for locating and squaring the patterns or guides upon the table.

30 The locating table 12 is provided with a plurality of intersecting T-grooves 74, the under cut portions 75 of which are adapted to receive the head 76 of the threaded pin 78, Fig. 5, passing through the guide sleeve 79 and receiving thereon the milled nut 80 which co-operates with the head 76 to clamp 40 the sleeve 79 to the positioning table, whereby is formed a guiding lug adapted to be received in the guide bore 69 and thus position the guide 66 and pilot spindle 61 and consequently the drill spindle 32 and the 45 drill 35 or other tool.

45 It is noted that the base of the sleeve 79 is much larger than the threaded pin 78, whereby it is possible to set the sleeve eccentrically of the threaded pin and therefore possible to fix the sleeve considerably to one side or the other of the groove 74, when desired.

50 The operation of the machine so far described is as follows:

55 The work knee is suitably adjusted and the work piece properly adjusted thereon, and the guide sleeve or sleeves 79 are secured at points corresponding to where holes are to be bored in the work piece.

60 The arm 18 and the slide 24 are then moved by means of their rack and pinions until the bore 69 is over the sleeve 79, and the spindle 61 is then lowered until the bore 69 fits upon the sleeve 79 and the arms 18.

65 The support 24 is locked in this position,

after which the drill spindle 32 and with it the drill are lowered by means of the handle 31, whereupon a hole is drilled in the work piece, the drill being driven by the motor 52 by means of the connections 70 herebefore described.

The operation just described is then repeated for each sleeve 79 fixed to the positioning table.

Instead of the sleeves 79 being fixed to 75 the positioning table a pattern may be substituted, and a profiling tool and a pilot pin may be substituted for the drill 35 and the guide 66 respectively, and a profile of the pattern produced on the work piece as is 80 well known.

Also it is obvious that a drawing may be placed on the bracket 11 and the details thereof traced with a scribe substituted for the guide 66, whereby the object shown by 85 the drawing may be reproduced on the work piece by means of appropriate tools.

In Fig. 7, I show an alternative form of positioning table 90 provided with securing screws 91 and a positioning scale 92 similar to those shown in connection with the table 12. Instead, however, of the T-slots, I provide a group of screw holes 94 adapted to receive the screw 95 passing through a slot 96 in one end of the elongated plate 95 98 carrying fixed at the opposite end a positioning pin 99, the screw serving to fix the plate and therewith the pin 99 to the positioning table. The screw and slot connection serves to permit the fixing of the positioning pin in any position between any of the holes 94.

Obviously, when the pin 99 is used, the bore 69 in the guide 66 would be made to fit the pin.

105

I claim:

1. A drill-pilot machine comprising, a work-supporting means, a pilot, a rotatable drill, means for moving the pilot and the drill in parallel paths in conformity to each other, means for moving the pilot and the drill in the same path in conformity to each other and transversely to the first-mentioned paths, a positioning supporting means having means for engaging positioning gage-points therewith, gage-points for engaging the positioning supporting means at desired positioning locations, means for engaging the pilot with a gage-point when such gage-point is engaging the positioning supporting means, and means for rotating the drill; movement of the pilot and the drill in said paths in conformity to each other permitting working rotation of the drill in position in conformity to the pilot, when the pilot is in engagement with a gage-point which is engaging said positioning supporting means.

2. A drill-pilot machine comprising, a work-supporting means, a pilot, a rotatable drill, means for moving the pilot and the

130

drill in parallel paths in conformity to each other, means for moving the pilot and the drill in the same path in conformity to each other and transversely to the first-mentioned paths, means for moving the pilot vertically, means for moving the drill vertically, vertical movement of the pilot being independent of vertical movement of the drill, a positioning supporting means having means for 5 engaging positioning gage-points therewith, gage-points for engaging the positioning supporting means at desired positioning locations, means for engaging the pilot with a gage-point when such gage-point is engaging 10 the positioning supporting means, and means for rotating the drill; movement of the pilot and the drill in said paths in conformity to each other and vertical movement of the pilot and the drill permitting working 15 rotation of the drill in position in conformity to the pilot, when the pilot is in engagement with a gage-point which is engaging said positioning supporting means.

3. A drill-pilot machine comprising, a work supporting table, a pilot, a rotatable drill, slideable means for moving the pilot and the drill in parallel paths in conformity to each other, means for operating said slideable means, slideable means for moving the pilot and the drill in the same path in conformity to each other and transversely to the first-mentioned paths, means for operating the transversely slideable means, means for moving the pilot vertically, means for moving 25 the drill vertically, vertical movement of the pilot being independent of vertical movement of the drill, a positioning table having means for engaging positioning gage-points therewith, gage-points for engaging the positioning table at desired positioning locations, means for engaging the pilot with a gage-point when such gage-point is engaging the positioning table, and means for rotating the drill.

45 4. A drill-pilot machine comprising, a work-supporting table, a pilot, a rotatable drill, driving means having a counter-shaft and a shaft transverse thereto, sliding means engaging said transverse shaft and the drill for rotating the drill, slideable means for moving the pilot and the drill in parallel paths in conformity to each other, means for operating said slideable means, slideable means for moving the pilot and the drill in the same path in conformity to each other and transversely to the first-mentioned paths, means for operating the transversely slideable means, means for moving the pilot vertically, means for moving the drill vertically, vertical movement of the pilot being independent of vertical movement of the drill, a positioning table having means for engaging positioning gage-points therewith, gage-points for engaging the positioning table at desired positioning locations,

and means for engaging the pilot with a gage-point when such gage-point is engaging the positioning table.

5. A drill-pilot machine comprising, a work-supporting table, a horizontal support, a driving means having a counter-shaft and a shaft transverse thereto, a slide movable longitudinally in said support and having a transverse head-piece at an end, rack and pinion means for moving the longitudinal slide, a slide in said head-piece movable transversely to the longitudinal slide, rack and pinion means for moving the transverse slide, a pilot on the transverse slide adjacent to an end thereof and having an extending spindle with means for engagement at the lower end, a rotatable drill on the transverse slide adjacent to the end thereof opposite to the pilot, a gear slidably engaging said transverse shaft and engaging said drill for rotating the drill, means for moving the pilot vertically, means for moving the drill vertically, vertical movement of the pilot being independent of vertical movement of the drill, a positioning table having recess-means for engaging positioning gage-points therewith, gage-points for engaging the recess-means of the positioning table, and means for engaging the lower end of the pilot spindle and for engaging a gage-point when such gage-point is engaging the recess means for engagement of the positioning table.

6. A drill-pilot machine comprising, a work-supporting table, a horizontal support, a driving means having a counter-shaft and a shaft transverse thereto, a slide movable longitudinally in said support and having a transverse head-piece at an end, a rack on said longitudinal slide and a pinion on said support for moving the longitudinal slide, means for retaining the longitudinal slide in a desired position, a slide in said head-piece movable transversely to the longitudinal slide, a rack on the transverse slide and a pinion on the head-piece for moving the transverse slide, means for retaining the transverse slide in a desired position, a pilot on the transverse slide adjacent to an end thereof and having an extending spindle with a horizontally extending upwardly recessed lower end, a rotatable drill on the transverse slide adjacent to the end thereof opposite to the pilot having an extending spindle, a helix gear slidably engaging said transverse shaft and engaging the spindle of the drill for rotating the drill, a rack on the pilot spindle and a pinion on the transverse slide for moving the pilot vertically, a rack on the drill spindle and a pinion on the transverse slide for moving the drill vertically, a positioning table having recess means for engaging positioning gage-points therewith, gage-points for engaging the recess means of the positioning table, and a

member for engaging the recessed lower end of the pilot spindle and for engaging a gage-point when such gage-point is engaging the recess means for engagement of the positioning table.

7. In a drill-pilot machine comprising a rotatable drill, and means for rotating the drill, the drill being movable longitudinally of the drill-pilot machine and movable transversely to said machine in conformity to a pilot, the combination of a pilot having an extending spindle and adapted to move longitudinally of the drill-pilot machine and to move transversely to said machine, said spindle having means for engagement at its lower end, a positioning table having recess means for engaging positioning gage-points therewith, gage-points having means at the lower ends for engaging the recess means for engagement of said table and having upwardly extending means for engagement, and a member having means for engaging the means for engagement at the lower end of the pilot spindle and for engaging the upwardly extending means for engagement of a gage-point when such gage-point is engaging the recess means for engagement of the positioning table.

8. In a drill-pilot machine comprising a rotatable drill, and means for rotating the drill, the drill being movable longitudinally of the drill-pilot machine and movable transversely to said machine in conformity to a pilot and being movable vertically, the combination of a pilot having an extending spindle and adapted to move longitudinally of the drill-pilot machine and to move transversely to said machine, and being movable vertically independently of the vertical movement of said drill, said spindle having a horizontally extended lower end with an upwardly extending recess therein, a positioning table having inverted T shaped recesses for engaging positioning gage-points therewith, gage-points for engaging the recesses of the positioning table, each gage-point consisting of a bolt head and a stem for engaging an inverted T shaped recess and an upwardly extending sleeve on said stem for engaging the positioning table, and a member having an upwardly recessed lower portion for engaging the sleeve of a gage-point and having an upwardly extending portion for engaging the recess in the lower end of said pilot spindle.

9. In a drill-pilot machine comprising a rotatable drill, and means for rotating the drill, the drill being movable longitudinally of the drill-pilot machine and movable transversely to said machine in conformity to a pilot, and being movable vertically, the combination of a pilot having an extending spindle and adapted to move longitudinally of the drill-pilot machine and to move

transversely to said machine, and being movable vertically independently of the vertical movement of said drill, said spindle having a horizontally extended lower end with an upwardly extending recess therein, a positioning table having inverted T shaped recesses for engaging positioning gage-points therewith, gage-points for engaging the inverted T shaped recesses of the positioning table, each gage-point consisting of a bolt head and a stem and an upwardly extending sleeve loosely engaging said stem, for engaging the positioning table and for permitting engagement of said sleeve with said table eccentrically of said stem, and means for adjusting the engagement of said sleeve with said table, a member having an upwardly recessed lower portion for engaging the sleeve of a gage-point and having an upwardly extending portion for engaging the recess at the lower end of said pilot spindle, and means for retaining said member in engagement with the recess in said spindle.

10. In a machine of the character described, the combination of a movable support; a slide slidable on said support; a pilot and a tool carried on said slide and disposed transversely to the path of the slide, said pilot and tool being movable entirely independently of each other transversely to said path, the tool being movable when the pilot is fixed; means for locking said support and slide; a positioning table associated with the pilot and a work support associated with the tool and movable independently of said positioning table toward or away from the tool.

11. In a machine of the character described, the combination of a horizontally movable support; a slide horizontally movable on said support; a pilot and a tool vertically mounted on said slide and each adapted for movement entirely independent of the other; means for moving or holding stationary either the pilot or the tool entirely independently of the other means for locking said support and said slide; a positioning table beneath the pilot; and a work support beneath the tool, and vertically movable entirely independently of the positioning table.

12. In a machine of the character described, the combination of a movable support; a slide slidable on said support; a pilot and a tool carried on said slide and disposed transversely to the path of the slide, said pilot and tool being movable entirely independently of each other transversely to said path; a positioning table associated with the pilot; a work support associated with the tool, and positioning means adjustably secured on the table and adapted to be engaged by the pilot.

13. In a machine of the character de-

scribed, the combination of a movable support; a slide slideable on said support; a pilot and a tool carried on said slide, and disposed transversely to the path of the 5 slide, said pilot and tool being movable entirely independently of each other transversely to said path; a positioning table associated with the pilot; a work support associated with the tool; an upstanding posi-

tioning means adjustably secured to the po- 10 sitioning table; and a guide carried on the lower end of the pilot and provided with a bore adapted to receive said positioning means.

JAMES POWERS.
